UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed May 27, 1924. Serial No. 716,096.

This invention relates to ribbon mechanism for front-strike writing machines of the character in which either one or another color of a ribbon may be used at will.

5 The improvement is illustrated in connection with a machine having a bichrome ribbon mechanism in which two fields of color are united in a single ribbon, and in which a shift device is provided to cause either of the colors to be brought into the field to cover the printing point at the type strokes.

One feature of the invention contemplates improved and simplified means for vibrating the ribbon to the printing field, the 15 mechanism operating to prevent overthrow of the ribbon carrier.

Another feature of the invention embodies the provision of mechanism including adjustment notches and a detent for engagement with the notches to set the mechanism to obtain the desired movement of the ribbon vibrator for throwing either color of a bichrome ribbon into the printing field or to render the ribbon mechanism inactive.

20 The notches are adjustable with relation to each other to provide for accurately adjusting the ribbon stroke to the typing field. Thus the stroke of the ribbon may be accurately adjusted to bring the exact mid 25 portion of either color-band to the center of the types. This insures against two-color printing or bleeding.

Another feature is the provision of a ribbon vibrator guided by thin flanges on the 30 sides of the type-guide, the flanges projecting beyond the top of the type guide, so as to accommodate the extreme movement of the ribbon vibrator.

A further feature of the invention provides a three position control for the ribbon carrier, comprising a handle at the front of the machine provided with a suitable index, and having connections to the ribbon-vibrator so that either color of the 35 bichrome ribbon may be accurately brought to the printing point, or the vibrator may be rendered inactive so as to enable the type to write off from the ribbon when the machine is employed to cut stencils. In ribbon-shifting devices, including a handle which may be set to three positions for the red and black fields of the ribbon, and a stencil position, there is a tendency to accidentally shift the handle into the stencil 40 position when the middle position is desired.

To eliminate such possibility the control mechanism is designed with a view to requiring a special effort on the part of the operator to shift the handle into the stencil position.

60 The parts are made of sheet-metal stamped and pressed to form, so as to enable their manufacture at low cost. This also contributes to lightness which is desirable in portable machines.

65 Other features and advantages will hereinafter appear.

In the accompanying drawings,

Figure 1 is a longitudinal vertical section approximately through the center of 70 the machine.

Figure 2 is a plan view of portions of the right-hand side of the machine.

Figure 3 is a front elevation of the extreme right-hand corner of the machine.

75 Figure 4 is a front view of the ribbon-carrier and its associated type-guide.

Figure 5 is a plan view of the ribbon-carrier.

80 Figure 6 is an enlarged vertical section, showing the carriage-feeding elements and the ribbon-vibrating and shifting mechanism.

Figure 7 is a front elevation of some of the parts shown at Figure 6.

85 Figure 8 is a plan view of the ribbon-vibrator and its associated parts.

Figure 9 is a two-position view, showing the operative positions of several parts connected to the ribbon-vibrator for the upper 90 or normal field of the ribbon.

Figure 10 is a view similar to Figure 9, except that the parts are shown positioned for the lower field of the ribbon.

95 Figures 11, 12 and 13 are detail positional views, illustrating the control of the ribbon-vibrator.

Figure 14 is a fragmentary view of the escapement rocker and its operating lever.

100 In the embodiment illustrated, 14 indicates a series of key-levers formed in different lengths to provide four different banks to constitute a standard keyboard. Each key-lever 14 operates to vibrate a bell-crank 15 that swings about a pivot-rod 16, to cause a connection 17 to vibrate its associated type-bar 18 about its pivot 19, to throw said type-bar from its position of rest against its pad 20 to its printing position against a 105 platen 21 at each downward stroke of the 110

key. The pivot 19 comprises a circular wire adjustably secured to a type-bar segment 22 provided with radial slots to guide the type bars to a common printing point; said segment may be suspended from suitable ears 23 forming part of the frame of the machine. The carriage-shift-frame comprises an end plate 24 at either side, these plates being joined together by a back plate 25, 10 and suspended at both sides upon pivots mounted on the free ends of levers 27 and 28 that may be journaled to the rear frame of the machine in such a manner that said carriage-shift-frame may be shifted between 15 two stop positions indicated at 29, where adjustable stops are secured to the frame of the machine. 30 indicates a frame formed with a flat section 31 and ears 32 at either side. These ears extend rearwardly and are 20 pivotally connected at 33 to the lower ends of arms 34 forming a swinging member pivoted to the rear frame, as at 35. The forward end of this frame 30, is formed with a tongue 36, first bent upwardly at right-angles 25 and then forwardly at right-angles. The free end of the tongue 36 passes through a slot in the segment 22. From this description it will be seen that said frame 30 will have a three-point bearing and will move 30 to and fro through a plane practically at right-angles to the plane of the segment 22. A spring 37 arranged underneath the section 31 is secured at one end to an ear forming part of said frame, and at the other end attached to a stationary part of a brace 38. The tension of the spring tends to move the 35 whole frame forwardly against a fixed stop 39.

Upon the front face of the back plate 25 40 a stationary stud 40 provides a bearing for an escapement-wheel 41 and an escapement pinion 42. To co-operate with the escapement-wheel 41 suitable escapement dogs 43 are mounted upon an escapement rocker 44, 45 pivotally hung between suitable brackets secured to the back plate 25. The lower end of the rocker 44 extends downwardly and terminates at a curved tongue 45 positioned to co-operate with a stud 46 arranged at the 50 end of a link 47 and pivotally connected to a pull rod 48 that extends forwardly to the front of the machine, where the free end is pivoted to the upper end of an arm 49 mounted at the center of a rock-shaft 50. 55 Arms 50', secured adjacent the extremities of the rock-shaft 50, extend forwardly under the type-keys of the machine and terminate in upturned ends for connection to a space-bar 51. A suitable spring 52 coiled about the 60 rock-shaft 50 has one end bent around the outer edge of the arm 49 and its other end bearing against the front plate of the machine to force the arm 49 rearwardly toward said front plate. From this construction, 65 it will be seen that the depression of the

space-bar 51 causes its intermediate connections to the carriage rocker to impart movement to the rocker 44, thus promoting a letter-space movement of the carriage. The space-bar 51 has no connection whatever to 70 the ribbon-vibrating mechanism, to be presently described.

53 indicates an interponent on the section 31 and is so arranged to move in unison with the frame 30 that the rear end 54 75 may engage with an arm 55 fixed in the carriage rocker, and thus provides means for operating the escapement rocker 44. By referring to Figures 6, 7 and 8, 56 indicates a bracket adjustably secured to the back 80 plate 25. This bracket extends outwardly at right angles to the back plate, and is then bent parallel with said plate, with the free end again bent forwardly to stand at right angles to said plate and provide a suitable 85 support for a ribbon-vibrator and ribbon-shifting mechanism. The ribbon-vibrator 57 includes a U-shaped section at one end mounted upon a shouldered screw 58 secured to the bracket 56. This vibrator 57 90 includes a long goose-neck arm or vibrating arm extending forwardly to a position immediately at the rear of the segment 22, where the free end is provided with a transverse pin 59 to provide a pivotal bearing for 95 the lower end of a ribbon-carrier 60. The vibrator 57 is also provided with a short arm 57' parallel with the vibrator, and between these two arms a transverse pivot is arranged to provide a bearing between said arms for a U-shaped yoke 61 comprising 100 two parallel arms that are joined at the free ends by a shouldered stud 62, and form an actuator. The stud 62 engages within a slotted ear 63 permanently fixed to the section 31, and arranged to stand at right angles thereto. When motion is given the frame 30 in either direction, the ear 63, moving in unison therewith, will engage 105 with the stud 62 and cause the yoke 61 to vibrate about its pivot between the two arms 110 of the ribbon-vibrator 57.

The bracket 56 is formed with an arm 26 that extends forwardly over the frame 30, said arm being perforated at the free end to provide a bearing for a rock-shaft 64, positioned to align with the normal position of the stud 62, said rock-shaft extending across the machine and taking a bearing in the side frame. Upon the rock-shaft 64, adjacent its bearing in the bracket 56, a yoke piece 65 is permanently fixed, the yoke piece comprising an ear 66 at one side formed with an open slot to engage with the stud 62, and a second ear 67 arranged parallel to the ear 66 to provide detent means through the co-operation of a spring 68, to lock or locate said shaft 64 at any one of three positions defined by suitable notches cut in the edge of said detent ear. These 115 120 125 130

detent positions may be rendered adjustable by the arrangement of two shoes 67^a and 67^b, arranged one over the other, and each formed with a notch to co-operate with the 5 spring 68 and permanently secured to the face of the ear 67 by suitable screws.

The brace 38 is located approximately centrally with respect to the inner sides of the frame of the machine, and functions to relieve strain upon the type-bar segment and undue vibration resulting from operations 10 of the key-levers and type-bars. This brace may comprise a sheet-metal support or casting and includes arms 38' and 40', and a mid 15 portion 41' having perforations through which securing screws 42' pass to a fastening lug 43' carried by a fulcrum plate 44' which supports the bell-crank 15. The arm 38' is directed rearwardly from the mid 20 portion 41', and is curved up adjacent its extremity and formed with a lug 45' arranged to face against the rear wall of the type-bar segment 22 near its lower end, and is secured thereto by a suitable screw 46'. The 25 curved arm 38' thus provides a substantial support and means for bracing the type-bar segment in a direction opposed to the strokes of the type-bars, and effectually eliminates vibration or strain. The arm 40' is directed 30 forwardly and upwardly to the bottom central portion of the type-basket 47', the end of the arm carrying a perforated fastening lug 48' through the medium of which the arm is secured to the underside of the type-basket by screws, rivets or in any other manner found suitable. As the type-basket 47' is supported at each end by a bracket 75 of the frame of the machine (see Figures 1 and 3) and intermediate the ends thereof by the arm 35 40' vibration is entirely overcome.

69 indicates a universal bar having a curvature to align with a circular groove at the rear of type-bar segment 22, the bar being suspended in this position by suitable ears 45 formed in the bar that may be riveted or otherwise secured to ears on the frame 30. The movement of each type-bar 18, in traveling to the printing position, will strike the universal bar 69, in advance of the printing 50 position and force the frame 30, and the several parts mounted thereon, rearwardly in unison with said bar; and under the recoil of the spring 37, when the type-bar returns to its pad, frame 30 and the universal bar 55 will be restored to normal position.

The rock-shaft 64, at a point adjacent the side frame of the machine, is provided with an arm 70 with its free end connected to a wire 71 that passes upwardly and then forwardly under the ribbon-spool towards the front of the machine, where the free end is formed with an eye to engage with a stud 72 fixed to one arm of a bell-crank 73, pivotally mounted upon a stud 74 fixed to a bracket 65 74' which is attached to a part of the bracket

75. This stud 74, as shown at Figure 1, is provided with a compression spring 72' between the bell crank and the head of the stud, to provide a flexible joint at this point, and permits a finger-knob 75', that co-operates within an irregular slot 76 in the front plate of the machine, to have sufficient latitude in any direction to form an interlock with different stop positions, as shown at Figure 3, where the finger-knob 75' is shown 75 at three positions. These positions may be indexed by the use of three different colors adjacent the three shift positions. The left-hand position R indicates the lower field; the middle position B, the upper field of the 80 ribbon, and the right-hand position S, the inactive, or where the ribbon-actuator is silent. It will be noted that in shifting from the position B to the position S there is a shoulder 76' to be overcome. This shoulder 85 is provided to prevent any tendency to accidentally shift the finger-knob into stencil position when middle position is desired.

By referring now more particularly to Figure 7, the yoke piece comprising the two ears 66 and 67 is positioned in this figure to show the co-operation of the other parts associated with the ribbon-vibrator 57 that renders said vibrator inoperative relative to an upward stroke through the movement of the stud 62 through the open slot in ear 66 without resistance. This movement is shown at Figures 11, 12 and 13. At Figure 11 the frame 30 is supposed to move in the direction of the arrow through an impulse from the universal bar 69, and move the slotted ear 63 in unison therewith, to the dotted-line position shown in this figure, and in so doing will cause the yoke piece 61 to follow the movement of the slot, and during this movement the stud 62 that also engages with the slot in the ear 66 will pass through said slot from the position of Figure 12 to the position shown at Figure 13 without opposition from the slot to cause a throw of the yoke 61 and ribbon-vibrator 57, the yoke idly rotating about its pivot. During this operation the yoke piece 61 has been vibrated in unison with the frame 30, and the movement of the frame has operated the carriage-feeding elements to provide a letter-space movement, the ribbon-vibrator 57 has remained inactive, and the ribbon has not been vibrated to cover the printing position on the platen. Figures 1, 2, 3 and 8 illustrate a means for controlling the ribbon-vibrator, and the different positions may be read from the red, black and white areas indexed at a front shield plate 77. By referring to Figure 9, it is assumed that the finger-knob 75' has been moved to the intermediate position shown at Figure 3, in section, which indicates the upper field of the ribbon. Here the yoke piece, through the movement of the bell-crank 73 and its connection to the arm 70, 120 125 130

has rotated with the rock-shaft 64; and the 5 detent spring 68 has been brought into locking position with the middle detent in the edge of the shoe 67^a. The rotation of these parts, as shown in Figure 9, has thrown the open slot in the ear 66 to a new angular position, and, when the frame 30 is vibrated rearwardly, the slotted ear 63, through the engagement of the stud 62, will cause the 10 yoke piece 61 to rotate about its pivot. In moving rearwardly with the frame 30, the stud 62 engages the lower edge of the stationary slot in the ear 66, and this slot becomes a camming element to force the yoke 15 piece 61 upwardly, and, through its pivotal connection with the ribbon-vibrator 57, both the yoke piece and ribbon-vibrator will move in unison, and, in passing from the full-line position at Figure 9 to the dotted position, 20 will cause the ribbon-carrier 60 to raise the upper half of the ribbon into position to cover the printing field of the types at the platen. Upon the return of the frame 30 slotted ear 63 will carry the stud 62 forwardly, and, in swinging the yoke piece 61 about its pivot, will allow the ribbon-vibrator 57 to drop to normal position.

In most two-color ribbon mechanisms the red section, which is not used frequently, is 30 adjusted in the machine with the red as the lower half of the ribbon, because to bring the red section or the lower half to the printing position will require a longer stroke of the vibrator. When it is desired to print 35 through this lower half of the ribbon the finger-knob 75' will be moved to the extreme left in Figure 3 to stand over the left-hand index which is supposed to index red. This movement of the bell-crank causes the arm 40 70 to shift to a new position, and, in shifting, to rotate the shaft 64. In this position the two ears 66 and 67 have rotated to cause the slot in the ear 66 to assume a more acute angular stop position, so that the detent 45 spring 68 will engage with the third notch in the shoe 67^b. Here it will be seen that the open slot of the ear 66 has assumed a more acute angular relation to the stud 62, and when the ear 63 that engages with the 50 stud is moved rearwardly with the frame 30, the yoke piece 61 will not rotate freely about its pivot, but will almost immediately ride up the inclined edge of the slot and become a camming element to lift the vibrator 55 57 to the dotted position shown at Figure 10.

It will be seen that the slot in the ear 66 is effective to move the stud 62 positively in both directions and that the side edges of said slot provide stops which prevent over-thrown or bleeding of the ribbon.

The ribbon, in passing from the spool 78, passes over a conical idler roller 79 mounted vertically upon an ear formed in the spool cup, and this idler, through its tapering inclined faces, is designed to take up the slack

in the ribbon at the lower edge, due to the passage of said ribbon from a vertical spool to the angular field of the ribbon-carrier 60 at the center of the machine. The ribbon-carrier, in vibrating upwardly to bring either one of the ribbon fields to the printing point on the platen, will have exactly the same movements without any change in leverage when the carriage is shifted to upper case position to print capital letters and through the same printing field of the ribbon. This is due to the fact that the ribbon-spools 78 and ribbon carrier 60 are both mounted to shift with the carriage when a shift-key, not shown, is depressed. During this shifting movement of the carriage, the stud 62 rises toward the outer end of the slot in the ear 63, but this movement does not increase or diminish the leverage of the ribbon-vibrator 57 or any of its associated parts; said stud simply engaging said slot nearer its open end, as shown at Figure 11.

A type-guide includes a base 80 fixed to the upper front edge of the segment 22 and a relatively short and thick stem-portion 83 formed with thin parallel flanged edges 84 for supporting and guiding the ribbon carrier 60 in its movements to and from the printing position. These flanged edges are extended beyond the top of the type-guide, as illustrated at 85, so that they may accommodate an extreme throw of the ribbon carrier.

The ribbon carrier 60, as shown at Figures 4 and 5, comprises two upright sections forming a fork 81 to straddle the typing position, and each section formed with an ear 82 bent around to embrace the edges 84 of the type-guide for support and guidance. Each section adjacent the edges of the guides is bent towards its adjacent ribbon-spool and this bent section comprises an open angular slot through which the ribbon is threaded; and through the joint action of the bend in the carrier and the angular slot, the slack in one edge of the ribbon is taken up, and the ribbon assumes a uniform flat field and has no tendency to curl.

From this description, it will be seen that the ribbon carrier is suspended by the ribbon-vibrator and guided by ears that embrace the parallel edges of the type-guide; that when the carriage is shifted, the carrier is raised a carriage-shift-distance and from this new position on the guide, it will be vibrated to cover and uncover the printing position.

It is to be understood that wherever the terms "vibrating arm" or "actuating arm" are used throughout the specification or claims, said terms include any suitable form of vibrator or actuator.

Variations may be resorted to within the scope of the invention, and portions of the improvements may be used without others.

Having thus described my invention, I claim:

1. In a typewriting machine, in combination, a main frame, a shift frame movable to different case positions relative to said main frame, keys, a universal bar for said keys, ribbon-vibrating mechanism mounted in said shift frame reciprocating at type-strokes of the universal bar, said ribbon-vibrating mechanism including a vibrating arm, an actuating arm therefor, a member having an inclinable slot arranged to slidably receive the free end of the actuating arm, means for varying the effective angle of said inclinable slot, and a universal bar actuated frame mounted for movement relative to the shift frame including a sliding connection to the free end of the actuating arm, said sliding connection arranged to transmit motion from the universal bar to the actuating arm to cause a throw of the vibrating arm and to permit free movement of the shift frame from one case position to another while preserving an invariable movement transmitting connection between the ribbon-vibrating mechanism and its operating means.

2. In a typewriting machine, in combination, a main frame, a shift frame movable to different case positions relative to said main frame, keys, a universal bar for said keys, ribbon-vibrating mechanism mounted in said shift frame reciprocating at type-strokes of the universal bar, said ribbon-vibrating mechanism including a vibrating arm, an actuating arm therefor, a member having an inclinable slot arranged to slidably receive the free end of the actuating arm, means for selectively varying the effective angle of said inclinable slot, and a universal bar actuated frame mounted for movement relative to the shift frame and including a slot substantially parallel to the direction of movement of the shift frame, said slot receiving the free end of the actuating arm to transmit motion from the universal bar to the vibrating arm and to permit free movement of the shift frame from one case position to another, while preserving an invariable movement transmitting connection between the ribbon-vibrating mechanism and its operating means.

3. In a typewriting machine, the combination with a platen and a universal bar, of a multi-color-ribbon-vibrating mechanism including a vibrating arm, an actuating arm associated with said vibrating arm, an element reciprocating at strokes of the universal bar and imparting idle motion to the actuating arm, a device including a stationary inclinable surface disposed in the path of motion of said actuating arm, said surface effecting a camming action against said actuating arm to cause a throw of the vibrating arm, and means for adjusting the degree

of inclination of said stationary surface to vary the extent of throw of said vibrating arm, whereby any selected color-band of the ribbon may be presented at the printing line.

4. In a typewriting machine, the combination with a platen and a universal bar, of a multi-color-ribbon-vibrating mechanism including a vibrating arm, an actuating arm associated with said vibrating arm, an element reciprocating at strokes of the universal bar and imparting idle motion to the actuating arm, a device including a stationary inclinable surface disposed in the path of motion of said actuating arm, said inclinable surface effecting a camming action against said actuating arm to cause a throw of the vibrating arm, said device also including means settable to determine the inclination of said surface to effect different throws of said vibrating arm, whereby to bring any selected color-band of the ribbon to the printing line, and means for effecting fine variations in the setting positions of said settable means, whereby any portion of a selected color-band may be presented at said printing line.

5. In a typewriting machine, the combination with a platen and a universal bar, of a multi-color-ribbon-vibrating mechanism including a vibrating arm, an actuating arm associated with said vibrating arm, an element reciprocating at strokes of the universal bar and imparting idle motion to the actuating arm, a device having a stationary inclinable slot, the free end of the actuating arm being arranged to ride in said stationary slot to cause a throw of the vibrating arm, and means for setting said slot to different selective angular positions to determine the throw of said vibrating arm or to render the same inactive.

6. In a typewriting machine, the combination with a platen and a universal bar, of a multi-color-ribbon-vibrating mechanism including a vibrating arm, an actuating arm associated with said vibrating arm, an element reciprocating at strokes of the universal bar and imparting idle motion to the actuating arm, a device having a stationary inclinable slot in which the free end of said actuating arm moves and is guided, said slot being effective to cause a throw of the vibrating arm upon operation of the universal bar, means for selectively positioning said slot at any one of a number of different angles corresponding to throws of the vibrating arm for the different color-bands, and means for effecting fine variations in the selective working positions of said slot, whereby any portion of any color-band may be presented at the printing line.

7. In a typewriting machine, the combination with a platen and a universal bar, of a multi-color-ribbon vibrating mechanism including a vibrating arm and a ribbon-carrier

connected thereto, an actuating arm associated with the vibrating arm, means operated by the universal bar and imparting idle motion to the actuating arm, and a device including a stationary inclinable surface which is settable at different angles in the path of motion of said actuating arm, said surface effecting a lifting of said actuating arm to cause a throw of the vibrating arm, the settable device including a sector having a series of notches adjustable with respect to one another, and a detent for engaging the notches.

8. In a typewriting machine, the combination with a platen and a universal bar, of a multi-color-ribbon-vibrating mechanism including a vibrating arm and a ribbon-carrier connected thereto and mounted upon a stationary part of the machine, an actuating arm having one end movably connected to the vibrating arm, means operated by the universal bar and imparting idle motion to the free end of said actuating arm, and a stationary sector having a slot therein, the free end of the actuating arm being arranged to ride in the slot, said sector being adjustable to control the angle of the slot with relation to the motion of the free end of said actuating arm, the slot being effective to cause said actuating arm to raise the vibrating arm to present the ribbon at the printing line of the platen, the sector-adjusting means including notches and a detent for engaging the notches to determine said angle of the slot corresponding to the different color-bands, said notches also being adjustable relatively to one another to effect fine variations in the extent of throw of the vibrating arm, for said different color-bands.

9. In a typewriting machine, the combination with a platen and a universal bar, of a multi-color-ribbon-vibrating mechanism including a vibrating arm and a ribbon-carrier connected thereto, the vibrating arm being rockably mounted upon a stationary part of the machine, an actuating arm pivotally connected to the vibrating arm at a point between said ribbon-carrier and the rocking point of the vibrating arm, means driven by the universal bar and imparting idle motion to the free end of said actuating arm, said free end having a pin, and a device including a stationary sector having a slot therein, said pin being arranged to ride in the slot, said sector being adjustable to control the angular position of the slot with relation to the direction of motion of said free end of the actuating arm, the latter effecting a lift of the vibrating arm corresponding to the angle of the slot, whereby one color-band or another is presented to the printing line of the platen.

10. In a typewriting machine, the combination with a platen and a universal bar,

of a multi-color-ribbon-vibrating mechanism including a vibrating arm and a ribbon-carrier connected thereto, the vibrating arm being rockably mounted upon a stationary part of the machine, an actuating arm pivotally connected to the vibrating arm at a point between said ribbon-carrier and the rocking point of the vibrating arm, means driven by the universal bar and imparting idle motion to the free end of said actuating arm, said free end having a pin, and a device including a stationary sector having a slot therein, said pin being arranged to ride in the slot, said sector having a fixed notch corresponding to a position in which the slot is ineffective to operate the actuating arm to vibrate the ribbon, a series of notches adjustable with respect to one another and to the fixed notch, and a stationary detent selectively engageable with any of said notches, the adjustable notches corresponding to different angular positions of the slot, whereby any color-band of the ribbon may be presented at the printing line of the platen.

11. In a typewriting machine, the combination with a platen and a universal bar, of a multi-color-ribbon-vibrating mechanism including a vibrating arm and a ribbon-carrier connected thereto, the vibrating arm being rockably mounted upon a stationary part of the machine, an actuating arm pivotally connected to the vibrating arm at a point between said ribbon-carrier and the rocking point of the vibrating arm, means driven by the universal bar and imparting idle motion to the free end of said actuating arm, said free end having a pin, a device including a stationary sector having a slot therein, said pin being arranged to ride in the slot, said sector having a fixed notch corresponding to a position in which the slot is ineffective to operate the actuating arm to vibrate the ribbon, a series of notched elements having radial slots, headed screws extending through said radial slots and into the body of the sector, whereby said notched elements are adjustable with relation to one another and also to the stationary notch, a stationary detent for selectively engaging any one of the notches to predetermine the angular position of the sector-slot with relation to the direction of motion of the free end of said actuating arm, a shaft upon which said sector is mounted, an index-device at the front of the machine and including a slot having an offset to form an abutment, the slot being continued to a point beyond said abutment, a finger-knob including a stem which is guided by said slot, and linkage between the finger-knob and the shaft, said finger-knob being operable to rotate the shaft to the different notch-positions of the detent, whereby any selected color-band may be presented to the platen.

at the printing line, the abutment-portion of the slot of said index-device providing a stop corresponding to the notch-position for one color-band of the ribbon, the end of said slot opposite the abutment corresponding to the detent-position for another color-band of the ribbon, the continued portion of the slot being effective to determine the silent position of the ribbon.

12. In a typewriting machine, the combination with a platen and a type-bar segment, of a type-guide including a base fastened to said segment, said type-guide also including a relatively short and thick stem portion terminating at its upper end in guides for the type, said stem being reduced at its side edges to form thin flanges, and a ribbon-carrier including eyes for the ribbon and tabs bent around said thin flanges, close beneath the eyes, to support and guide said carrier, said flanges being extended beyond the top of the guides for the type, whereby the carrier is supported in an extreme throw of the ribbon above said relatively short stem.

13. In a typewriting machine, the combination with a varied path ribbon-vibrating mechanism including means for setting the mechanism, so as to control the extent of movement of a ribbon-carrying vibrating element to two positions of a bichrome ribbon, or rendering said mechanism ineffective to move the ribbon, of a frame having a slot opening formed with an offset providing a shoulder in said frame, and a connection from the setting means arranged to ride in the slot to regulate the adjustment of said setting means, said shoulder acting as a stop in the path of movement of the connection, so as to prevent a direct throw of said connection from ribbon-vibrating position to the position in which the mechanism is ineffective to vibrate the ribbon.

14. In a typewriting machine, the combination with a varied path ribbon-vibrating mechanism including means for setting the mechanism so as to control the extent of movement of a ribbon-carrying vibrating element to two printing positions of a bichrome ribbon, or rendering said mechanism ineffective to move the ribbon, of a frame having a slot opening therein, said slot having a double right angular bend intermediate its extremities to form an offset slot and a shoulder in the frame, a bell-crank lever pivoted for movement adjacent the slot, one arm of the lever terminating in a handle arranged to ride in the slot to regulate the shift of the setting means, an operating connection between the setting means and the other arm of the lever, means for causing the handle to bear against one edge of the slot, the shoulder formed by said offset slot providing a stop in the path of movement of the handle, so as to prevent a direct throw

of said handle from the ribbon-vibrating position to the position in which the mechanism is ineffective to vibrate the ribbon, and means for identifying the different setting positions of the mechanism controlling the extent of movement of the ribbon-carrying vibrating element.

15. In a typewriting machine, the combination with varied path ribbon-vibrating mechanism including means for setting the mechanism, so as to control the extent of movement of a ribbon-carrying vibrating element to two positions of a bichrome ribbon, or rendering the mechanism inoperative to move the ribbon, of a frame having a slot formed with a double rightangular bend to provide an abutment intermediate its extremities, and a connection from the setting means arranged to ride in the slot to regulate the adjustment of said setting means, said abutment acting as a stop in a straight path of movement of the connection, from one end of said slot to said abutment, so as to prevent a direct throw of said connection from ribbon-vibrating position to the position in which the ribbon-vibrating mechanism is inactive, the other end of the slot being in a plane to one side of the aforementioned portion of the slot, due to said double right-angular bend and constituting the position of said connection for silencing said vibrating element.

16. In a typewriting machine, ribbon-vibrating mechanism including a vibrating arm, an actuating arm associated with the vibrating arm, a revolvably shiftable member formed with an arcuate edge having a series of notches, a detent engaging the notches to hold the member in position, said member also having a slot, the free end of said actuating arm being arranged to slide in the slot, means for imparting motion to the actuating arm, said slot being inclinable at an angle to the direction of movement of said motion-imparting means to cause a throw of the vibrating arm when said actuating arm is operated, and means for relatively varying the effective angle of said slot.

17. In a typewriting machine, ribbon-vibrating mechanism including a vibrating arm, an actuating arm associated with the vibrating arm, a revolvably shiftable member formed with an arcuate edge, separate shoe pieces having notches therein adjustably secured around said arcuate edge, so as to adjustably vary the distances between the notches, a detent engaging the notches to hold the member in position, said member also having a slot, the free end of said actuating arm being arranged to slide in the slot, means for imparting motion to the actuating arm, said slot being inclinable at an angle to the direction of movement of said motion-imparting means to cause a throw of

the vibrating arm when said actuating arm is operated, and means for relatively varying the effective angle of said slot.

18. In a typewriting machine, a ribbon-
5 throw setting device including a sector, a series of separate shoe-pieces adjustable with respect to each other arranged around the curved face of the sector, each of said shoe-pieces having a notch therein, means
10 for securing the shoe-pieces to the sector, and a detent for engagement with said notches to maintain the sector at any one of a number of different angles.

19. In a typewriting machine, a ribbon-
15 throw setting device including a sector, a series of separately adjustable shoe-pieces arranged around the curved face of the sector, said shoe-pieces having slots, set screws passing through the slots into the sector,
20 each of said shoe-pieces having a notch in its outer face, and a detent for engagement with the notches.

20. In a typewriting machine, ribbon-vibrating mechanism including a vibrating arm, an actuating arm associated with the 25 vibrating arm, a revolubly shiftable member having an arcuate edge, separate shoe-pieces having slots therein, said shoe-pieces arranged around said arcuate edge, set screws passing through the slots into the shiftable member to adjustably secure the shoe-pieces thereto, said shoe-pieces having notches formed in their outer faces, a detent 30 engaging the notches to hold said member in adjusted position, said member also having a slot, the free end of said actuating arm being arranged to ride in the slot, and means for imparting motion to the actuating arm, said slot being inclinable at an angle to the 35 direction of movement of said motion-imparting means to cause a throw of the vibrating arm when said actuating arm is operated.

ALFRED G. F. KUROWSKI.
